Primary Examiner — Daniel D Bui*Assistant Examiner* — Andrew Kerr(74) *Attorney, Agent, or Firm* — Christensen O'Connor Johnson Kindness PLLC(57) **CLAIM**

The ornamental design for a tribblade, as shown and described.

DESCRIPTION

FIG. 1 is a perspective view of a tribblade showing my new design;

FIG. 2 is another perspective view thereof;

FIG. 3 is another perspective view thereof;

FIG. 4 is a side view thereof;

FIG. 5 is another side view thereof;

FIG. 6 is a bottom view thereof; and,

FIG. 7 is a top view thereof.

The broken lines in FIGS. 1-7 depict unclaimed environmental subject matter and form no part of the claimed design.
